UNITED STATES PATENT OFFICE.

JOHN M. EWIG, OF NEW LEXINGTON, OHIO, ASSIGNOR OF ONE-THIRD TO EDGAR CHUTE AND ONE-THIRD TO C. H. WISE, BOTH OF NEW LEXINGTON, OHIO.

RAILWAY-TIE HOLDER.

Application filed September 8, 1926. Serial No. 134,280.

The present invention relates to improvements in rail laying equipment and has particular reference to an improved tie holding device. An important object of the invention is to provide an improved tie holding tool which will greatly facilitate the laying and replacement of railway ties.

A further object of the invention is the provision of a tool of the above character 10 designed to firmly grip a railroad rail and permit of proper connection with the tie to hold the same in position against the underside of the rail.

A still further object of the invention is 15 the provision of a tool of the above type which will greatly lessen the labor incident to the laying of the railroad tie and permit the same to be properly held in position while driving the retaining spikes.

20 Another object of the invention is the provision of a tie holding tool which is simple and durable of construction, compact in design and which can be manufactured at a relatively low cost.

25 Other objects and advantages of the invention will become apparent as the description progresses.

In the accompanying drawing forming a 30 part of this specification and in which like reference characters are employed to designate corresponding parts through the same:

Figure 1 is a side elevation of a tool constructed in accordance with my invention 35 shown in operative position in association with a rail and tie,

Figure 2 is a top plan view of the tool, 40 Figure 3 is an enlarged vertical transverse sectional view taken on the line 3-3 of Figure 1, and

Figure 4 is a similar view taken on the line 4-4 of Figure 1.

Referring to the drawing, wherein for the purpose of illustration is shown a preferred 45 embodiment of my invention, the numeral 10 generally designates the conventional form of railway tie shown in Figure 1 in operative position with respect to a pair of railway rails 11. It is customary, in initially 50 laying the ties or replacing the same, to securely hold the tie in its proper position with respect to the rail and then drive the securing spikes. At the present time, this is accomplished in various ways, usually em-

ploying an apparatus which is cumbersome 55 to handle and requires considerable time in the attachment thereof.

My invention is particularly designed to provide a tie laying tool of a simple nature which will expedite the securing of the rail to the tie. With this in mind, my improved tool consists of a lever 12 comprising a straight body 13 having a longitudinal handle portion 14 inclined upward at an obtuse angle with respect to the body portion 13 and terminating in an enlarged hand grip 15. Formed adjacent the hand grip of the handle is an upwardly extended apertured ear 16 the purpose of which will later appear. The inner or rear end of the lever is formed 60 to provide an angular tie engaging projection comprising an upwardly projecting arm 17 and a transversely projecting horizontal arm 18 adapted to bear against the underside of the tie as will be more specifically 65 described hereinafter.

Pivotedly connected with the lever 12 is a clamping bar 19 comprising a bar portion 20 and an arcuate downwardly projecting extension 21. The lower extremity of the extension 21 is pivotally connected with the lever by means of a pivot pin 22. As shown to advantage in Figure 1, the outer edge of the extension 21 is serrated to provide rack teeth 23. The outer end of the bar 20 is 70 bent upon itself to provide an integral rail gripping jaw 24, this jaw being arranged to firmly grip the inner base flange of the rail 11. A jaw 25 comprising an angular jaw member is pivotally connected to the bar 20 75 by means of a pivot pin 26 preferably provided with a nut on one end for tightening the said jaw in locked position. By this construction it will be noted that the clamping member 19 is disposed in an offset position relative to the lever body 13 and extends upwardly and outwardly therefrom.

In order to facilitate operation of the lever 12 with respect to the auxiliary gripping member 19 suitable automatic locking mechanism is provided consisting of a pivoted pawl 27 arranged for engagement with the ratchet teeth 23. Pivotedly connected with the ear 16 is an angular hand lever 28 having a portion 29. A connecting rod 30 is connected to the portion 29 and to the pawl 27. The pawl is normally held in engagement with the ratchet teeth by a leaf spring 100 105

31 secured to the forward end of the lever handle 14 and disposed between the same and the hand lever 28.

In use, the rail holding device is initially 5 secured to the flange of the rail by slidably fitting the jaw 24 about the inner side of the rail base flange and adjusting the movable jaw 25 to engage the outer side of the flange, as illustrated in Figure 1 of the drawing. The jaw 25 is secured in position by 10 tightening the nut carried by the pivot pin. The rail tie 10 is then arranged in position beneath the rail and so that one end will rest upon the arm 18 of the lever. The outer 15 handle of the lever is then swung downwardly causing the inner tie engaging end to be swung upwardly against the tie and thus position the tie firmly against the lower face of the rail flange. The tie may be locked in 20 this position by releasing the hand lever 28 so that the pawl 27 will engage the ratchet teeth 23. It is apparent, however, that during the downward swinging movement of the lever handle the hand lever is depressed, 25 that is, the handle 28 is forced downwardly toward the lever handle to effect retraction of the pawl 27. When the hand is removed from the hand lever 28 the pawl is automatically thrown into engagement with the 30 ratchet teeth and the lever locked with relation to the rail gripping member 19 so that the tie 10 will be firmly pressed against the rail flange while the spikes are driven in place.

35 Thus, a simple and durable tie holding structure is provided, combining a compact as well as a conveniently operable structure which will greatly facilitate the attachment of the ties to the rails.

40 It is to be understood that the form of my invention herewith shown and described is to be taken as the preferred example of the same, and that various changes as to the shape, size and arrangement of parts may 45 be resorted to without departing from the spirit of the invention or the scope of the subjoined claims.

Having thus described my invention, what I claim is:

50 1. A tie holding device comprising a lever, an offset projection formed at the outer end of the lever adapted to engage the under side

of a tie, a gripping member extending above the projection of the lever and beyond the same, the member having an arcuate portion 55 pivotally connected with the intermediate portion of the lever and provided with ratchet teeth, a jaw at the outer end of the gripping member adapted to engage the inner base flange of a rail, an adjustable jaw 60 carried by the gripping member adapted to engage the outer base flange of a rail, a pawl pivotally connected with the lever adjacent the gripping member and adapted to normally engage the ratchet teeth on the gripping 65 member, and means for actuating the pawl.

2. A tie holding device comprising a lever, an angular projection formed on the outer end of the lever including a vertical arm and an arm extending laterally from 70 the upper end of the vertical arm and adapted to engage the under surface of a rail tie, a rail gripping member pivotally connected with the lever and including a body portion extending above the laterally extending arm 75 of the lever and projecting outwardly beyond the same, an integral jaw formed on the outer end of the rail gripping member adapted to engage the inner side of a rail base flange, the gripper member having an 80 arcuate portion provided with ratchet teeth, an adjustable jaw mounted on the gripping member adapted to engage the outer side of a rail base flange, a pawl pivotally connected to the lever and engageable with the 85 ratchet teeth on the rail gripping member, and means carried by the lever operable to activate the pawl.

3. A device of the class described comprising a lever having an angular tie engaging portion at its outer end, a gripping member pivotally connected with the lever and extending in an elevated position above and outwardly beyond the engaging portion of the lever, gripping jaws at the outer end 95 of the said gripping member to engage the opposite sides of the base flange of a rail, and means for locking the lever and gripping member in position with the said engaging portion of the lever in clamping engagement with the under side of the tie.

In testimony whereof I affix my signature.

JOHN M. EWIG.
